UNITED STATES PATENT OFFICE.

GUSTAVUS A. SCHLECHTER, OF READING, PENNSYLVANIA.

DESIGN FOR A BADGE.

SPECIFICATION forming part of Design No. 21,745, dated August 2, 1892.

Application filed June 27, 1892. Serial No. 438,214. Term of patent 3½ years.

To all whom it may concern:

Be it known that I, GUSTAVUS A. SCHLECHTER, a citizen of the United States, residing at Reading, in the county of Berks, State of Pennsylvania, have invented a certain new and original Design for Badges, of which the following is a specification.

The drawing illustrates my design, the leading feature of which is the representation of a baldric or shoulder-belt. The baldric is bent midway of its length and the ends are crossed and fastened as though ready for use. At the crossing-point of the ends is the representation of a Maltese cross. Further ornamentation appears both upon the outside and re-

verse faces, a portion of the latter showing in perspective, and suitable lettering may be placed upon the intermediate space. At the bend of the baldric is the representation of a dagger-handle, of which the securing-pin represents the blade.

What I claim is—

The design for a badge, substantially as shown and described.

In testimony whereof I affix my signature in presence of two witnesses.

GUSTAVUS A. SCHLECHTER.

Witnesses:

M. H. DAVIS,
J. WARREN TRYON.
